UNITED STATES PATENT OFFICE

2,413,511

CUTTING MACHINE

Louis V. Lucia, West Hartford, Conn.

Application November 29, 1943, Serial No. 512,223

21 Claims. (Cl. 26—7)

1

This invention relates to cutting machines and more particularly to machines for cutting Venetian blind tape such as clearly described in my co-pending application Serial No. 445,213, filed May 30, 1942, now Patent No. 2,347,603.

The object of this invention is to provide improved and further simplified means for cutting the Venetian blind tape.

Other objects and advantages of the invention will be more clearly understood from the following description and from the accompanying drawings in which:

Fig. 1 is a plan view of a cutting machine embodying my invention.

Fig. 2 is a side view thereof.

Fig. 3 is a fragmentary plan view on an enlarged scale illustrating the operation of one of the cutting units of the machine.

Fig. 4 is a view in vertical section on line 4—4 of Fig. 3.

As illustrated in the drawings, my improved machine comprises a bed 5 having thereon the cutting mechanism which includes feed rollers 6—6, for feeding the tape 7 through the machine, and a suitable tensioning mechanism, as indicated generally at 8, for applying tension to the tape, all of which is described in my above mentioned co-pending application.

In the form of my invention which is described herein, I provide a plurality of cutters in the form of scissors 9 which are carried on a disk, or frame, 10 that is rotatably mounted on a post 11 upon the bed 5 and adjacent to the side of the tape 7 as it is moved through the machine. A similar set of cutters is mounted on the other side of the tape 7 so that both sides of the tape may be cut at the same time.

If desired, each set of cutters may be constructed so that the disk member 10 will have projections or blades 12 thereon each of which forms one blade of a scissors. The other blade of the scissors consists of a member 13 which is pivoted as at 14 on said member 10.

Each of the said blades 13 is provided with an extension 15 having a stud 16 thereon. A spring 17 is provided for retaining the scissor in open position by urging the extension 15 against a stop pin 18 which is mounted on the disk 10 as clearly shown in the drawings.

An operating cam member 19 is preferably mounted upon the post 11 and is adjustably secured thereto by means of a screw 20.

The operation of my improved cutting machine is as follows.

The tape 7 is first placed in the machine, as

2

clearly described in my co-pending application, by positioning it between the feed roll 6 and the tensioning mechanism 8. The two strips of the Venetian blind tape are then separated and the cross threads or straps, indicated at 21, which are to be cut in the machine, are placed in mesh with the projections 12 of the scissor units so that the scissors, or cutters, are actually geared to the cross threads as clearly illustrated in Fig. 3. The tape is then moved through the machine by the feed rolls 6—6 which are driven by the motor indicated at 22 and pull the tape through the machine against the tension applied thereon between tension plates 8—a and 8—b. During the movement of the tape, each set of cross threads in the tape is brought into contact with one of the extensions 12 and thereby rotate the disk 10 so that all of the scissors of the unit are kept in mesh with the cross threads of the moving tape.

As each set of cross threads, or straps, moves into engagement with the blade 12 of its corresponding scissor and rotates the disk 10, the stud 16 on the extension 15 will engage the cam 19 and thereby cause the scissors to close and cut the cross threads as it is moving therewith; see Fig. 3. After the cross threads have been cut and the scissors has moved out of engagement with the cam 19, the spring 17 will again open the scissor so that it will be ready to receive its next corresponding cross thread as it is carried past the tape by the rotation of the disk 10.

It will be understood, from the above description, that the cutting mechanism is operated entirely by the movement of the tape through the machine and that no extra driving means is necessary for driving the cutting means.

The cam 19 is stationary on the post 11 but adjustable thereon, by means of the screw 20, so that the said cam may be timed to cause the scissors to close when in proper position and while in engagement with the cross threads when they are disposed within the scissors.

It will be clearly seen from Fig. 3 that, just as one group of cross threads is being severed by its corresponding scissor, the following scissor is ready to receive and be moved by the next group of cross threads; thus continuous rotation of the scissor carrying disk 10 is maintained by the tape as it moves through the machine.

As illustrated in Fig. 4, the scissor carrying member 10 may be mounted to be positioned between the hub 26 of the cam 19 and the disk 10 and it may be adjusted for the proper tension by vertical adjustment of the cam on the

post 11, to provide the necessary amount of friction against the rotation of the disk 10 to prevent the scissors from running ahead of the cross threads in the tape and thereby keeping the scissors in proper contact with the cross threads as they are engaged thereby and the said threads are being cut by the scissors.

As shown in Fig. 3, the scissor may be constructed so that they each will include a plate 28 which carries the blades 12 and 13 thereon and is adjustably secured to the disk 10 by means of screws 29-29 that extend through slots 30-30 in said plate. The cam 19 may be made adjustable by means of an extension plate 31 secured to a projecting portion 32 on the hub 20 by a screw 33 that extends through the slot 34. This construction will permit radial adjustment of the scissors for varying the spacing between them in accordance with the spacing between the cross threads of different sizes and types of tapes and thereby permit the use of the same cutting unit on differently spaced cross threads. It will be understood that the cam 19 may be adjusted for the lengths required to operate the scissors in their different positional adjustments. Lateral adjustment of each scissor unit, so that the blades 12 and 13 will project for the proper distance into the tape, may be made by sliding the support 35 on the bed 5 and securing it in proper position by means of the screw 36 which extends through the slot 37.

I claim:

1. In a machine for Venetian blind tape including adjacent strips connected by cross threads, means for moving said tape through said machine, and cutting means including a plurality of cutters in mesh with said cross threads and operated thereby for cutting said cross threads while rotated about an axis.

2. In a machine for cutting spaced cross threads of Venetian blind tape, means for moving said tape through said machine, and cutting means including a plurality of cutters continuously in mesh with said cross threads and rotated about an axis thereby for cutting said cross threads during the movement of said tape.

3. In a machine for cutting spaced cross threads of Venetian blind tape, means for moving said tape through said machine, cutting means including a plurality of cutters rotated around an axis and continuously in mesh with said cross threads, and means for operating said cutters to cut said cross threads during the movement of said tape.

4. A cutting machine for cutting spaced cross threads of Venetian blind tape including means for moving said tape through the machine, cutting means including a plurality of cutters carried around a central axis and continuously moving with said tape by engagement with said cross threads, and stationary means for operating said cutters during their movement to cut said cross threads.

5. A cutting machine of the character described for cutting spaced cross threads of Venetian blind tape, said machine including means for moving said tape through the machine, means for retaining said tape under tension during the movement thereof, and a cutter mechanism located at one side of said tape; said cutter mechanism including a plurality of cutters carried around a central axis and adapted to engage and move with said cross threads during the movement of said tape, and fixed cam means adapted

to operate each of said cutters while in motion and at a pre-determined position.

6. A machine for cutting spaced cross threads in Venetian blind tape which includes mechanism for moving the tape through the machine under tension, and a cutter mechanism located at one side of said tape and rotated thereby; said cutter mechanism including a plurality of cutters, and means for operating said cutters while in engagement with said cross threads for cutting said cross threads.

7. A machine for cutting spaced cross threads in Venetian blind tape including means for feeding the tape through the machine, means for retaining the tape under tension, and a cutter mechanism located at one side of the tape and actuated by said cross threads; said cutting mechanism including a rotatable member having a plurality of cutters extending therefrom and adapted to mesh with the said cross threads, and a stationary member adapted to engage said cutters and operate them to cut said cross threads while in motion.

8. A machine for cutting spaced cross threads in Venetian blind tape including means for moving the tape through the machine, and a cutting mechanism; said cutting mechanism including a rotatable member located at one side of the tape, a plurality of cutters extending from said member, and adapted to mesh with said cross threads, and a stationary cam member adapted to actuate said cutters individually to cut said cross threads upon reaching a pre-determined position.

9. A machine for cutting spaced cross threads in Venetian blind tape which includes means for moving the tape through the machine, and a cutting mechanism actuated by said tape; said cutting mechanism including a rotatable member having a plurality of scissors extending therefrom and adapted to receive said cross threads during the movement thereof, and a fixed operating member for operating said scissors upon reaching a pre-determined position; each of said scissors including a pivoted cutting blade having an extension thereon adapted to engage said operating member as the scissors moves past the same and close the said scissors to cut the cross threads engaged thereby.

10. A machine for cutting spaced cross threads in Venetian blind tape including means for feeding the tape through the machine, and a cutting mechanism; said cutting mechanism including a member rotatable on an axis spaced from the tape and having a plurality of scissors extending therefrom and adapted to enter between the straps of the tape and receive the cross threads, a stationary cam adapted to close the scissors while the cross threads are positioned therein, and spring means for normally retaining said shears in open position.

11. A machine of the character described including a mechanism for moving Venetian blind tape therethrough under tension, and a cutter mechanism including a rotatable member deriving rotation from the movement of said tape; the said member carrying a plurality of scissors which extend therefrom and are each adapted to receive a cross thread in said tape, and a stationary member for closing the said scissors while in register with the cross threads.

12. In a machine for cutting spaced cross threads in a tape of textile material, means for moving said tape through the machine, a cutting mechanism including a plurality of cutters rotatable about an axis spaced from said tape and

adapted to move with and contact said cross threads, a stationary member for operating said cutters to cut said cross threads at a predetermined position during the continuous movement thereof, and means for adjusting said stationary member for pre-determining said position.

13. In a machine for cutting spaced cross threads between adjacent strips of textile material, means for moving said tape through the machine, a cutting mechanism comprising a rotatable member having a plurality of spaced scissors extending therefrom and adapted to engage and cut said cross threads; each of said scissors including a blade fixed to said rotatable member, a pivoted blade, and stationary means for operating said pivoted blade.

14. In a machine for cutting spaced cross threads between adjacent strips of textile material, means for moving said tape through the machine, a cutting mechanism comprising a rotatable member having a plurality of scissors extending therefrom and adapted to receive said cross threads during continuous movement of the tape, a stationary member for operating said scissors to cut said cross threads when in predetermined position relative thereto, and means for adjusting said scissors to vary the spacing thereof in accordance with the spacing of said cross threads.

15. A cutting machine as set forth in claim 14 including means for adjusting said operating means in accordance with the adjustment of the said scissors.

16. In a machine for cutting spaced cross threads in a tape of textile material, means for moving said tape through the machine, a cutting mechanism including a post spaced from said tape, a rotatable member on said post, a plurality of cutters carried on said rotatable member and adapted to engage said cross threads and thereby rotate said member, and stationary means extending from said post and adapted to

successively operate said cutters during the movement thereof while in cutting position relative to said cross threads.

17. In a machine for cutting spaced cross threads in a textile tape, a cutting mechanism including a plurality of cutters rotatable about an axis spaced from the tape and adapted to be engaged by said cross threads and rotated thereby, and means for successively operating each of said cutters to cut said cross threads while moving therewith.

18. In a machine for cutting spaced portions in a strip of material, means for moving said strip through the machine, cutting means actuated by and continuously moving with said strip, and stationary means for operating said cutting means to cut said spaced portions.

19. In a machine for Venetian blind tape including adjacent strips connected by cross threads or straps, means for moving said tape through the machine, and cutting means continually movable with said tape and operable for cutting said cross threads or straps during the movement of said tape.

20. In a machine for Venetian blind tape including adjacent straps connected by cross threads or straps, means for moving said tape through the machine, an operating member, and a cutting mechanism including a plurality of cutters continuously moving with said tape and operable by said operating member, upon said cutters passing the same, for cutting said cross threads during the movement of said tape through the machine.

21. In a machine for cutting a portion in a tape-like material, means for moving said material in the machine, a cutter adapted to be engaged by said portion and moved thereby, and means rendered operable by the movement of the cutter to cause operation of said cutter to cut said portion.

LOUIS V. LUCIA.
